MOTORCYCLE JACK

Thomas R. Rumsey, P.O. Box 2512, Culver City, Calif.

Filed July 17, 1964, Ser. No. 80,913

Term of patent 3½ years

(Cl. D41—1)

FIG.1.

FIG.2.

FIG.3.

FIG.4.

FIGURE 1 is a perspective view of a motorcycle jack showing my new design;

FIGURE 2 is a top plan view thereof;

FIGURE 3 is an end elevational view thereof illustrating the right hand end of the plan view of FIGURE 2; and

FIGURE 4 is a side elevational view thereof.

I claim:

The ornamental design for a motorcycle jack, substantially as shown.
